Attorney

UNITED STATES PATENT OFFICE.

FERRIS HADDAD, OF WINDBER, PENNSYLVANIA.

MUFFLER.

1,254,901.

Specification of Letters Patent. Patented Jan. 29, 1918.

Application filed February 7, 1917. Serial No. 147,215.

To all whom it may concern:

Be it known that I, FERRIS HADDAD, a citizen of the United States, residing at Windber, in the county of Somerset and State of Pennsylvania, have invented certain new and useful Improvements in Mufflers, of which the following is a specification, reference being had to the accompanying drawings.

10 This invention relates to certain improvements in mufflers and has relation more particularly to a device of this general character especially designed and adapted for use in connection with internal combustion engines of a type generally employed with motorcycles; and it is an object of the invention to provide a device of this general character with novel and improved means whereby the muffler may be readily cut out as may be required by the necessities of practice.

The invention consists in the details of construction and in the combination and arrangement of the several parts of my improved muffler whereby certain important advantages are attained and the device is rendered simpler, less expensive and otherwise more convenient and advantageous for use, all as will be hereinafter more fully set forth.

30 The novel features of the invention will hereinafter be definitely claimed.

In order that my invention may be the better understood, I will now proceed to describe the same with reference to the accompanying drawings, wherein—

Figure 1 is a view partly in elevation and partly in vertical section illustrating a muffler provided with an embodiment of my invention; and

40 Fig. 2 is a sectional view taken substantially on the line 2—2 of Fig. 1.

As disclosed in the accompanying drawings, M denotes a muffler of a type generally employed in connection with motorcycles and provided at its forward end portion with the head H, said head being provided in one of its sides with a port 1 affording communication with the housing 2 arranged at one side of said head. In communication 45 with the housing 2 through the forward end thereof are the pipes 3 leading from the exhausts of the cylinders of the motor (not shown) and which may be of any ordinary or preferred type. It is also to be understood that the number of pipes 3 depend

upon the number of cylinders comprised in the motor.

The rear wall of the housing 2 is provided with an opening 4 substantially rectangular in form and which serves to afford communication direct with the atmosphere. The opening 4 is adapted to be closed by the valve V herein disclosed as a flat plate hingedly connected, as at 5, to the rear wall of the housing 2 adjacent an end of the opening 4 and preferably the upper end whereby said valve V is arranged for swinging movement in a substantially vertical path.

As herein embodied, the valve V comprises a plate 6 of a width and length in excess of the corresponding dimensions of the opening 4 and the inner face of the plate 6 has secured thereto a supplemental plate 7 adapted to snugly fit within the opening 4 when the valve V is in closed position. It is also to be noted that the plate 6 is of such a width as to extend beyond the outer side of the housing 2 so that the same may be readily engaged by a foot to force the valve 80 V into closed position.

It is thought to be self-evident that when the valve V is closed the exhaust from the motor will be directed through the muffler but when the valve V is open the exhaust 85 will pass directly to the atmosphere.

Underlying the bottom wall of the housing 2 is a spring member S formed of flat material and having its forward end portion suitably anchored, as at 8, to the under 90 surface of the housing 2, and said spring member S extends a material distance to the rear of the rear wall of the housing 2.

At a point immediately adjacent the rear wall of the housing 2, the spring member S 95 is offset upwardly, as indicated at 9, to afford a shoulder to overlie the lower or free end portion of the valve V, whereby said valve V may be effectively maintained in closed position. Upon depressing the free 100 end portion of the spring member S the valve V is adapted to be automatically opened or swung upwardly through the medium of the retractile member 10 anchored at one end to the outwardly disposed lug 11 105 carried by the valve V and suitably secured at its opposite end to the upper wall of the housing 2.

The outer or free end portion of the spring member S is also adapted to be en- 110

gaged by a foot so that the same may be depressed sufficiently to permit the release of the valve V. The movement of the spring member S under pressure of a foot or otherwise is limited by the loop member 12 carried by the bottom wall of the housing 2 and extending slightly beyond the rear wall of said housing and through which the spring member S is directed. The valve V 10 is returned to closed position by a foot as the position of a muffler in the general type of motorcycle readily permits this operation.

As herein embodied, the retractile member 10 is disclosed as a conventional coil spring.

From the foregoing description, it is thought to be obvious that a muffler constructed in accordance with my invention 20 is of an extremely simple and comparatively inexpensive nature and is particularly well adapted for use by reason of the convenience and facility with which it may be assembled, and it will also be obvious that my invention 25 is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

35 In combination with a muffler, a housing disposed at one side of the muffler at an

end portion thereof and in communication therewith, said housing being provided with an induction opening, the face of the housing opposed to said induction opening being open, an upwardly swinging valve co-acting with said open face and hingedly connected with the top of the housing, the intermediate portion of the valve snugly fitting within the housing, a resilient member 40 secured at one end to the bottom of the housing, said member being of such a length as to extend in advance of the open face of the housing, said resilient member being provided with a shoulder overlying the free 45 end portion of the valve for maintaining the valve in closed position, the portion of the resilient member in advance of the shoulder being of such a length as to permit the same to be readily engaged by a foot of a person, 50 a loop extending from the bottom of the housing forwardly of the open face of the casing and through which the resilient member is directed, a portion of the resilient member in advance of the shoulder contacting with said loop for limiting the downward movement of the resilient member, and automatic means for opening the valve upon release of the shoulder of the resilient member 55 from the valve upon depression of the free end portion of said resilient member.

In testimony whereof I hereunto affix my signature in the presence of two witnesses.

FERRIS HADDAD.
